UNITED STATES PATENT OFFICE.

CHARLES DOERING, JR., AND HENRY H. DOERING, OF OAK PARK, ILLINOIS.

DESIGN FOR A HOUSING FOR A BEVERAGE-DISPENSING APPARATUS.

47,453.

Specification for Design.

Patented June 15, 1915.

Application filed February 23, 1915. Serial No. 10,149. Term of patent 7 years.

To all whom it may concern:

Be it known that we, CHARLES DOERING, Jr., and HENRY H. DOERING, both citizens of the United States, residing at Oak Park, in the county of Cook and State of Illinois, have invented a new, original, and ornamental Design for a Housing for a Beverage-Dispensing Apparatus, of which the following is a specification, reference being had to the accompanying drawing, forming a part thereof.

In the accompanying drawings illustrating the invention: Figure —1— is a per-

spective view of a housing for a beverage dispensing apparatus embodying our design. Fig. —2— is a top plan view of the same.

We claim:

The ornamental design for a housing for a beverage dispensing apparatus as shown.

CHARLES DOERING, JR.
HENRY H. DOERING.
